UNITED STATES PATENT OFFICE.

HOMER B. MARCH, OF MUSKEGON, MICHIGAN, ASSIGNOR, BY MESNE ASSIGNMENTS,
TO THE AUTOMATIC IRRIGATION COMPANY, OF MUSKEGON, MICHIGAN, A COR-
PORATION OF MICHIGAN.

NOZZLE.

Application filed January 10, 1923. Serial No. 611,742.

To all whom it may concern:

Be it known that I, HOMER B. MARCH, a citizen of the United States, residing at Muskegon, in the county of Muskegon and State of Michigan, have invented new and useful Improvements in Nozzles, of which the following is a specification.

The present invention relates to nozzles, particularly such as are employed to vent water from the horizontally disposed water pipes of an irrigating or sprinkling system; and its object is to provide such a nozzle having a deflector adapted to be bent into a set position to direct the water issuing from the nozzle in a desired direction; and further to provide an improved screen for such a nozzle whereby any solid matter in suspension in the water may be prevented from stopping or interfering with the flow 20 of the water through the nozzle.

This and any other objects hereinafter appearing are attained by, and the invention finds preferable embodiment in, the structure hereinafter particularly described 25 in the body of this specification and illustrated by the accompanying drawings, in which:—

Figure 1 is a vertical central longitudinal sectional view of a portion of an irrigating pipe, to which my improved nozzles are applied, one of which is shown in central longitudinal section taken on line 1—1 of Figure 2;

Figure 2 is an under side view of the same, one of the nozzles being shown in transverse section taken on line 2—2 of Figure 1, and the other nozzle being shown in transverse section taken on line 2^a—2^a of Figure 1;

Figure 3 is a side view (reduced in size) of said pipe illustrating nozzles whose deflectors are bent to various set positions; and

Figure 4 is a transverse sectional view of the pipe taken on line 4—4 of Figure 3.

In the embodiment of my invention chosen for illustration by the drawings and for detailed description in the body of this specification, a portion of a horizontally disposed pipe 1 through which water for irrigating or sprinkling passes is shown, to which pipe are applied a plurality of my nozzles 2, spaced apart at desired intervals.

As thus illustrated, these nozzles are threaded into openings through the wall of the pipe. Each nozzle has a passage there-

through, the inner portion 3 of which passage is cross-sectionally larger than the vent or outer portion 4 thereof. A mesh screen 5 rolled or involuted about the longitudinal axis of said portion 3 of the passage is seated therein and, as shown, extends outwardly beyond the inner end 6 of the nozzle and into the interior of the pipe 1, and may be secured in position by a small lump of solder 7. It will be seen that by thus rolling the screen into the involute form shown the openings in one layer of the screen are disposed at varying distances from the openings in the adjacent layer or layers, so that a very perfect screening out of any solid matter suspended in the water is effected, and such matter is prevented from entering the vent 4 and thus stopping or interfering with the flow of the water therethrough.

The nozzle is furnished with a deflector 8, integral therewith and extending outwardly from the body portion 9 of the nozzle adjacent its vent 4. This deflector—or its restricted portion 10 adjacent the nozzle's body portion—is bendable so that the deflector may be bent into a set position as desired, in order that the stream issuing from the vent may be directed in a desired direction. As shown, the lateral surface 11 of the deflector is cross-sectionally convex and longitudinally concave, so that the water issuing from the vent may be not only deflected by the concavity of the deflector into the desired direction, but also spread laterally by the deflector's convexity.

In Figure 3 positions of the deflectors bent into different set positions is illustrated.

It will be readily understood that the screen may be removed from the nozzle and unrolled into flat form in which form it may be readily cleaned of clogging substances, and may then be again rolled into involuted or other cross-sectionally curved form and inserted into the nozzle; and that any bendable foraminous sheet, whether of mesh form or not, and whether involuted or bent into other cross-sectionally curved form, may be thus removed from the nozzle, flattened out for cleaning and again bent into such curved form and reinserted into the nozzle.

I claim:

1. In a device of the character described: a pipe having an opening through its side; 110

a nozzle having a passage therethrough and seated in said opening; a strainer formed from a foraminous sheet rolled into a substantially compact roll, its adjacent convolutions contacting each other, inserted into the nozzle's passage.

2. In a device of the character described: a pipe having an opening through its side; a nozzle having a passage therethrough and seated in said opening; a strainer formed from a foraminous sheet rolled into a substantially compact roll, its adjacent convolutions contacting each other, inserted

into the nozzle's passage and axially extending into the pipe transversely thereof. 15

3. A liquid strainer formed from a foraminous sheet rolled into a substantially compact roll, its adjacent convolutions contacting each other, and positioned axially- transversely to the flow of liquid screened 20 thereby.

In testimony whereof I have hereunto set my hand at Grand Rapids, Michigan, this 12th day of December, 1922.

HOMER B. MARCH.
